UNITED STATES PATENT OFFICE

ERNST SCHLÄFLI, OF BERN, SWITZERLAND, ASSIGNOR TO THE FIRM GOSO-MOP CONTINENTAL A.-G., OF BERN, SWITZERLAND, A CORPORATION OF SWITZERLAND

MOP

Application filed January 6, 1931, Serial No. 506,932, and in Germany January 27, 1930.

The present invention relates to a backing or strip for mops especially such mops combined with a wringing device. Such backings consisted heretofore of simple bunches of strings or of rows of strings sewed with much pain to a strip of cloth, but neither of these working forms could stand the wear and tear of such tools so that these working forms could hardly be introduced into the market.

The object of the present invention is a backing for mops of the kind mentioned and is characterized in that it comprises a strip of cloth having looped strings woven into the cloth in spaced rows. This weaving is effected in that the strings are arranged parallel to the weft by a number of warp threads. The loops are cut open afterwards and a very convenient manner of fastening the strings to the strip is obtained thereby.

The annexed drawings represent a working example of the object of the invention.

The Fig. 1 is a sectional view of the strip in its first stage of manufacturing,

25 The Fig. 2 a sectional view having the loops cut open,

And the Fig. 3 shows the apparatus for which the backing is intended.

The backing consists in a strip of cloth 10 having loops of string 11 held at their middle portion and woven into the cloth held by a spring 13 attached to the handle stick at 12 and hooked into a perforation made in a rod 14 inserted into a loop formed at the end of the cloth. Said spring maintains the cloth in its working position extended upon a frame formed of a cross bar 7 and a stiffening rib. While one end of the backing has been inserted between the rods 7 and 8 it is prevented from being withdrawn again by means of a rod 15 stuck into a loop formed at said end of the strip.

When replacing the strip the spring 13 must be unhooked and the rod 15 withdrawn from the respective loops, whereupon the strip may be withdrawn from between the rods 7 and 8.

50 The loops of string 11 are woven in continuously. They are parallel to the weft and perpendicular to the web of the fabric and

each loop is held by five warp threads. The loops are cut open afterwards so that the ends left will form a bunch together.

The kind of fastening forms a safe means of attaching the strings to the backing. The single strings cannot fall out and the frequent extending and contracting of the backing caused by its alternately getting wet and dry has no effect on the fastening.

What I claim as new is:

1. A process of manufacturing mops, which comprises weaving a strip of cloth and arranging looped strings perpendicular to the web of the fabric, and thereafter cutting the loops of the strings to provide the mop strings.

2. A process of manufacturing mops, which comprises weaving a strip of cloth and arranging looped strings perpendicular to the web of the fabric and perpendicular to the warp, and thereafter cutting the loops of the strings to provide the mop strings.

In testimony whereof I affix my signature.

ERNST SCHLÄFLI.
